CLAIM

The ornamental design for a camera stand, substantially as shown and described.

DESCRIPTION

FIG. 1 is a perspective view of a camera stand showing our new design;

FIG. 2 is a top view of FIG. 1;

FIG. 3 is a bottom view of FIG. 1;

FIG. 4 is a right side view of FIG. 1;

FIG. 5 is a left side view of FIG. 1;

FIG. 6 is a rear view of FIG. 1;

FIG. 7 is a front view of FIG. 1;

FIG. 8 is a perspective view of the camera stand of a camera stand showing with the rear leg in an extended position;

FIG. 9 is a top view of FIG. 8;

FIG. 10 is a bottom view of FIG. 8;

FIG. 11 is a right side view of FIG. 8;

FIG. 12 is a left side view of FIG. 8;

FIG. 13 is a rear view of FIG. 8; and,

FIG. 14 is a front view of FIG. 8.

Features illustrated in phantom using dashed lines (broken lines) are shown for exemplary purposes only and form no part of the claimed design.
